UNITED STATES PATENT OFFICE.

CLARK HOLDEN, OF BARRE, VERMONT.

BUSH-HAMMER.

SPECIFICATION forming part of Letters Patent No. 470,570, dated March 8, 1892.

Application filed July 30, 1891. Serial No. 401,132. (No model.)

To all whom it may concern.

Be it known that I, CLARK HOLDEN, of Barre, in the county of Washington and State of Vermont, have invented a new and Improved 5 Bush-Hammer, of which the following is a full, clear, and exact description.

The object of the invention is to provide a new and improved bush-hammer which is simple and durable in construction, securely 10 holds the blades in position, and permits of conveniently separating the several parts to take out the blades for sharpening or other purposes.

The invention consists of certain parts and 15 details and combinations of the same, as will be hereinafter described, and then pointed out in the claims.

Reference is to be had to the accompanying drawings, forming a part of this specification, 20 in which similar letters of reference indicate corresponding parts in all the figures.

Figure 1 is a perspective view of the improvement. Fig. 2 is a sectional side elevation of the same on the line 2 2 of Fig. 3. Fig. 25 3 is a sectional plan view of the same on the line 3 3 of Fig. 2, and Fig. 4 is a perspective view of one of the gibs.

The improved bush-hammer is provided with the two body-plates A and A', arranged 30 opposite each other and formed at their inner sides at the middle with bosses B and B', respectively, having a groove extending transversely to form an eye C for the handle of the hammer. At the ends of the bosses B and B' 35 are arranged the transversely-extending gibs D and D', provided at their middle with inwardly-extending tongues D² and D³, respectively, fitting into a corresponding V-shaped groove E, arranged longitudinally in the adjacent faces of the bosses B and B'. Bolts F and F' pass through the body-plates A A' and the tongues D² D³ to securely hold the plates 40 and gibs in position. Opposite the tongues D² and D³ are arranged grooves D⁴ and D⁵, respectively, in the gibs D and D', respectively, the said grooves being engaged by

tongues G² G³, formed on the inner ends of the sets of cutting-blades G G', held between the outer ends of the body-plates A A'.

In order to fasten the cutting-blades G G', 50 sets of bolts H H', respectively, are employed, passing through the body-plates A A' and the said sets of cutting-blades, as plainly illustrated in the drawings. It will be seen that by this arrangement the gibs D D' are securely 55 held in place between the body-plates A A', as all lateral motion is prevented by the tongues D² D³ engaging the longitudinal slot E in the bosses B B'. A like motion of the sets of cutting-blades G G' is prevented by 60 the said cutting-blades engaging with their tongues G² G³ the grooves D⁴ D⁵ in the gibs D D'.

Having thus fully described my invention, I claim as new and desire to secure by Letters 65 Patent—

1. A bush-hammer comprising oppositely-arranged body-plates having central bosses and transverse gibs fitted between the said plates on the ends of the bosses, each gib being provided with a tongue fitting into a longitudinal groove formed in the said bosses, and bolts passing through the said body-plates and through the said gibs to hold the body-plates and gibs in position, substantially 70 as shown and described.

2. A bush-hammer comprising oppositely-arranged body-plates having central bosses and transverse gibs fitted between the said plates on the ends of the bosses, each gib being provided with a tongue fitting into a longitudinal groove formed in the said bosses, sets of cutting-blades formed with tongues 80 engaging grooves in the said gibs, and bolts for fastening the said gibs to the said body-plates, and bolts for fastening the sets of blades between the body-plates, substantially as 85 shown and described.

CLARK HOLDEN.
